(57) **CLAIM**

The ornamental design for a rounded square display device for a cord, as shown and described.

DESCRIPTION

FIG. 1 is a perspective view of a rounded square display device for a cord of the present invention;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof;
FIG. 8 is a perspective view of the rounded square display device for a cord of FIG. 1 showing a representative design in broken lines on the front side of the device,
FIG. 9 is a front elevational view thereof;
FIG. 10 is a rear elevational view thereof;
FIG. 11 is a left side elevational view thereof;
FIG. 12 is a right side elevational view thereof;
FIG. 13 is a top plan view thereof; and,
FIG. 14 is a bottom plan view thereof.

The broken line showing of a logo on the front portion of the rounded square display device for a cord in FIGS. 8 and 9, is included for the purpose of illustrating exemplary indicia that forms no part of the claimed design.
